[57] **CLAIM**

The ornamental design for a transaction terminal and receipt printer, as shown and described.

DESCRIPTION

FIG. 1 is a perspective view of a transaction terminal and receipt printer showing our new design.

FIG. 2 is another perspective view of the transaction terminal and receipt printer shown in FIG. 1.

FIG. 3 is a top plan view of the transaction terminal and receipt printer shown in FIG. 1.

FIG. 4 is a right side elevational view of the transaction terminal and receipt printer shown in FIG. 1.

FIG. 5 is a left side elevational view of the transaction terminal and receipt printer shown in FIG. 1.

FIG. 6 is a front elevational view of the transaction terminal and receipt printer shown in FIG. 1; and,

FIG. 7 is a back elevational view of the transaction terminal and receipt printer shown in FIG. 1.

The bottom of the transaction terminal and receipt printer is unornamented and forms no part of our invention.
